UNITED STATES PATENT OFFICE.

JOHN S. TIMMONS, OF PHILADELPHIA, PENNSYLVANIA, ASSIGNOR TO TIMMONS TALKER, INC., OF PHILADELPHIA, PENNSYLVANIA, A CORPORATION OF PENNSYLVANIA.

DESIGN FOR A LOUD-SPEAKING DEVICE.

Application filed July 5, 1924. Serial No. 10,052. Term of patent 14 years.

To all whom it may concern:

Be it known that I, JOHN S. TIMMONS, a citizen of the United States, residing in Philadelphia, Pennsylvania, have invented a new, original, and ornamental Design for Loud-Speaking Device, of which the following is a specification, reference being had to the accompanying drawing, forming part

thereof, in which the single figure of the drawing is a perspective view of a loud-speaking device embodying my new design.

I claim:

The ornamental design for a loud-speaking device, as shown.

JOHN S. TIMMONS.
